LIQUID DISPENSING DEVICE

Hermann Lorant, Vienna, Austria

Application August 30, 1933, Serial No. 687,490
In Austria September 3, 1932

3 Claims. (Cl. 221—98)

In the majority of automatic coin-freeed machines for the dispensing of liquids in pre-determined quantities, and more particularly of petrol for lighters, at present in use the drawing of the liquid is as a rule effected by means of a scooping vessel provided within the container for the liquid.

It is clear that with this arrangement special means must be provided within the container for the actuation of the vessel, for which reason, for the purpose of dealing with defects, cleaning, etc., the container requires to be opened, and such opening in time impairs the essential liquid-tightness of the container. If the above-mentioned means for the lifting of the scooping vessel be arranged outside the container it becomes necessary to provide a number of apertures in the container which increase the danger of explosion due to evaporation. In other known automatic coin-freeed liquid-dispensing machines employing pumps, valves, or the like it has been altogether impossible hitherto to obtain satisfactory liquid-tightness, and thus to eliminate the danger of fire completely. Moreover all these types of apparatus have the drawback that not only evaporation but also dripping of the petrol occurs. Finally, the cost of manufacturing these types of apparatus is also comparatively high.

In accordance with the invention there is adopted an improved and hitherto not yet employed arrangement by which the above-mentioned drawbacks are obviated, and at the same time a very considerable simplification of the entire device is effected. The invention is based on the idea of fastening a measuring vessel immovably in the container, and that in such a manner that when the container is tilted a quantity of liquid predetermined by the cubic contents of the measuring vessel flows out automatically. This new principle, that is to say that of tilting the container together with the ladle, vessel, or the like situated therein is employed for the first time in the automatic coin-freeed machine according to the invention. The new automatic coin-freeed machine can be simply constructed so that the tilting of the container only becomes possible after the insertion of a coin. Further, the troublesome replenishing of the container with petrol can also be avoided, since the container of the automatic coin-freeed machine is simply exchanged for a fresh container, which is not easily possible in the case of other types of apparatus in which the above-mentioned special means are provided in or in connection with the container.

The invention is illustrated with the aid of a

constructional example, in the figures of the drawing, in which Fig. 1 shows the interior arrangement of the automatic coin-freeed machine, with the outside casing removed, in front elevation, Fig. 2 a side elevation of Fig. 1, with the releasing mechanism shown partly in section, and with the outside casing, Fig. 3 shows the device likewise in side elevation, but during the dispensing of the liquid, and Fig. 4 shows, finally, the arrangement for the tilting of the container, in plan view.

As is clear from Figs. 1 and 3, the liquid container 2 is mounted on the rear wall 1 of the casing of the automatic coin-freeed machine, by means of two parallel arms 3, 4. The mounting in these arms is however preferably effected not directly but, in the constructional example described, with the aid of a frame 5 which is rotatably mounted in the arms 3, 4, and which is at right angles to the latter when the apparatus is not in use. The container 2 possesses two or more screw bolts 6, 7, on to which screw threaded sleeves 8, which are guided in the upper part of the frame, can be screwed, so that in this manner the container 2 can be fixed in position in the frame 5 or liberated after the slackening of the screw threaded sleeves. The one screw bolt 6 at the same time takes the form of an outlet tube, and serves to establish communication between a discharge nozzle 9 attached to the screw threaded sleeve 8 and a tube 10 fixedly mounted within the container. This tube 10 leads to the measuring vessel 11 which is situated at the bottom of the container 2.

As above described, the measuring vessel 11 and the outflow pipe 10 are fixedly mounted within the container; the pipe 10 is disposed obliquely, at an angle to the discharge nozzle 9, so that when the container 2 is tilted from the position shown in Fig. 2 into the position shown in Fig. 3, that is to say on rotation through about 90°, the amount of liquid dispensed is precisely equal to the amount present in the vessel 11 when the latter is in the normal position (Fig. 1). After the discharge of this predetermined quantity of liquid the container 2 is tilted back again into the normal position shown in Fig. 2.

The actuation of the described device is best effected in practice by the arrangement that the container is tilted by means of a press-button, and restored to the normal position by the action of a recoil spring. The operation of the press-button is rendered possible only after the insertion of a coin; an arrangement of this nature is shown in Figs. 2 and 4.

The press-button 12, which is guided between two arms 27, 28, and which consists of a button portion proper and of a thrust rail, is provided with a pin 16 which is guided in a radial slot 15 5 in a coupling disc 29, and which is adapted to act upon this disc. The disc 29 is firmly connected by means of pegs 30 or the like to an extension 5' on the frame 5. Thus when pressure is exerted upon the thrust rail 12 the container will be 10 tilted through 90° into the position shown in Fig. 3. In order to permit of the carrying out of this movement, however, a spring pawl 18, which is pivoted on a pin 19, must first be brought out of engagement with an arresting notch in the 15 rail. This is effected by the insertion of a coin, by the arrangement that the coin inserted through the passage 28 drops upon a pin 21 extending laterally from the pawl, or upon a pin 21 attached to the rail 27. If pressure be then 20 applied to the part 12, the pin 16 attached to the thrust rail bears against the upper part of the coin, and depresses this latter together with the pawl 18, thereby permitting of the rail being moved further towards the right. The coin then 25 drops of its own accord into the collecting receptacle 22.

During the movement of the press-button 12 towards the right a spring 17, which bears against the pin 16, is compressed, so that, after the releasing of the press-button 12, when it is in the 30 position indicated in Fig. 3, the spring restores the same into the initial position, the container, which is positively connected with the rail 12, being likewise returned into its initial position. 35 At the same time the pawl 18 moves up again into the arresting position. The thrust rail 12 is guided on the one hand by the connecting pin between the two guiding members 27, 28, and on the other hand by a pin provided in the axis 40 of rotation of the container.

Any other desired releasing means which are 45 usual in connection with automatic coin-freeed machines can naturally be employed in connection with the device in accordance with the invention.

In Figs. 2 and 3 the outside casing 23 is also indicated. As will be seen, there are provided in this latter only three apertures, namely an aperture 24 for the insertion of money, an aperture 25 50 through which the end of the discharge nozzle

is brought out, and an aperture for the press-button 12. Laterally of the aperture 25 there is preferably provided on the casing 23 a protective cover 26, so that the lighter to be filled can be held at the right place in advance, before the 5 appearance of the nozzle 9. The measuring vessel 11 is preferably made very shallow, so that the automatic coin-freeed machine dispenses liquid even when the level of the latter is very low.

An essential advantage of the special arrangement of the discharge nozzle 9 resides in the fact that this latter, except for the short time during which the user of the automatic coin-freeed machine draws the petrol, remains constantly concealed in the upwardly pointing position, this 15 arrangement precluding any dripping and ensuring that the nozzle remains inaccessible from the outside.

Any desired known means usual in connection with automatic coin-freeed machines can be employed for rendering the apparatus inoperative. In the described automatic coin-freeed machine it will be advantageous to provide a ratchet wheel actuated by the press-button 12, which wheel after a certain number of revolutions thrusts a 25 lever under the coin slot 24, and thereby prevents the further insertion of money.

What I claim is:

1. A predetermined measure of delivery mechanism, including a casing, a container mounted 30 for tilting in the casing, means arranged in the container for delivering therefrom a predetermined quantity of fluid on the tilting of the container, means for tilting the container, and a nozzle carried by the container and extended 35 through the casing in the operative delivery position of the container.

2. A predetermined bulk delivery mechanism, including a casing, a container mounted for tilting therein, an outlet nozzle removably connected to the container and extending through the casing wall when the container is tilted, a bulk measuring device arranged in the container and in open communication with the nozzle, and a manually operable element for tilting the container from the exterior of the casing.

3. A construction as defined in claim 2, wherein means are provided for normally locking the operable element against operation.

HERMANN LORANT. 50
